UNITED STATES PATENT OFFICE.

CLARENCE V. PLUMB, OF LOS ANGELES, CALIFORNIA, ASSIGNOR TO INGERSOLL-RAND COMPANY, OF JERSEY CITY, NEW JERSEY, A CORPORATION OF NEW JERSEY.

ROCK-DRILL CENTRALIZER.

Application filed November 19, 1921, Serial No. 516,442. Renewed November 8, 1923.

To all whom it may concern:

Be it known that I, CLARENCE V. PLUMB, a citizen of the United States, residing at Los Angeles, in the county of Los Angeles and State of California, have invented a Rock-Drill Centralizer, of which the following is a specification accompanied by drawings.

This invention relates to rock drills of the hammer type but more particularly to a combined supporting bearing and guide or centralizer for the drill steel. The objects of this invention are to produce a relatively simple, practical and efficient structure that may be easily and quickly applied to or removed from the shell of a rock drill and which will serve to rigidly support the drill steel upon starting a hole.

A further object of my invention is to produce a combined support and guide that will greatly facilitate the starting of drill holes and particularly where the drill hole is to be formed on an angle in the face of a wall.

Further objects of the invention will hereinafter appear, and the invention consists in certain features of construction, arrangement of parts and combination of elements, and the invention is shown in one of its preferred forms in the accompanying drawings in which;

Fig. 1 is a top plan view of the forward end of the shell of a rock drill and showing my improved guide and support positioned thereupon,

Fig. 2 is a side elevational view of the guide and support in position for use,

Fig. 3 is an enlarged cross section taken on the line 3—3 of Fig. 2,

Fig. 4 is a perspective view of the bearing block for the drill shank,

Fig. 5 is a perspective view of the forward ends of the arms that support the drill shank bearing block, and

Fig. 6 is an enlarged cross section taken on the line 6—6 of Fig. 1.

Referring by numerals to the accompanying drawing, which illustrates a practical embodiment of my invention, 10 designates the shell of a rock drill in the sides of which are formed channels or guide-ways 11. My improved supporting bearing includes a pair of arms 12 and 13 having straight shanks at their rear ends 14 and said shanks are adapted to be positioned in the guide-ways

11, when the device is applied to the drill. The rear ends of the arms are adapted to frictionally grip the guideways 11 of the shell. The forward end of arm 12 is horizontally slotted to form a pair of plates 15 between which is positioned a plate 16 that is formed on the forward end of arm 13.

The plates 15 and 16 are provided with vertically aligned apertures 17 and the upper one of plates 15 is provided with notches 18 on opposite sides of the aperture in said plate.

Passing through an aperture 19 in the central portion of arm 12 is a rod 20 having a threaded end portion 21, that is seated in a threaded aperture in arm 13. The rear end of rod 20 is provided with a hand wheel 21 and secured to said rod adjacent to arm 12 is a collar or flange 22. As a result of the construction just described when rod 20 is rotated the arms 12 and 13 will be drawn toward or moved away from each other.

A plate 23 is provided on top of its end portions with oppositely arranged lugs 24 which preferably extend at substantially right angles from the arms 12 and 13 and in the inner faces of which are formed bearings 25 for the drill steel 26, and which latter is carried by the usual chuck 27.

Depending from the center of plate 23 is a pivot pin 28 that passes through the apertures 17 and the threaded lower end of said pin receives a nut 29. Formed on opposite sides of the pin 28 and immediately below plate 23 are lugs 30 that occupy the notches 18. By virtue of this construction when arms 12 and 13 are moved toward or away from each other, plate 23 will be slightly rotated owing to the arrangement of lugs 30 in notches 18. The lugs 24 are positioned on plate 23 so that when the arms 12 and 13 are moved toward each other, said lugs 24 having the bearings 25, will move away from drill steel 26 so that the combined support and bearing may be readily detached from the rock drill shell and drill steel.

The arms 12 and 13 are adapted to be held in the guideways of the shell in a plane substantially parallel to the plane of the shell guideways and may extend beyond the end of the shell in order that a steel of considerable length may be guided and supported thereby. After the drill has been moved

forwardly in the shell a sufficient distance to enable the forward end to come in contact with the rear lug 24 of the centralizer, further movement of the drill will force the 5 arms from their engagement with the shell.

A device of my improved construction is comparatively simple, may be easily applied to or removed from the shell of a rock drill, provides a firm and substantial bearing for 10 the drill steel and greatly facilitates the operation of the drill, particularly during the starting of drill holes or while drilling angular holes in the face of a wall.

The various parts of my improved drill 15 chuck guide may be modified and changed slightly in details without departing from the spirit of the invention, as set forth in the appended claims.

I claim as my invention:

20 1. In a rock drill, the combination with a shell, of a centralizer for guiding the drill steel, and means for causing said centralizer to frictionally grip said shell, tending to hold said centralizer stationary relative to 25 said shell.

2. In a rock drill, the combination with a shell, of a centralizer for guiding the drill steel, and means for frictionally holding said centralizer on the shell, said centralizer 30 being adapted to be forced from said shell by the forward end of the rock drill.

3. A combined support and guide for drill steels comprising a pair of pivotally connected arms, means for moving said arms 35 toward and away from each other, a member supported by the pivotally connected ends of said arms and bearings on said member for a drill steel.

4. In a rock drill steel guide, a pair of

arms pivotally connected at one end, a member supported by the pivotally connected ends of said arms and connected to one arm so as to move therewith and drill steel bearings on said member. 40

5. The combination with a rock drill and 45 its shell of a pair of pivotally connected arms detachably secured to the shell of the drill and a pair of drill steel bearings supported by said arms.

6. The combination with a rock drill and 50 its shell, of a pair of pivotally connected arms removably applied to the shell of the drill, a plate supported by said arms and connected to one arm so as to move therewith and a pair of drill steel bearing lugs 55 on said plate.

7. In a rock drill, the combination of a shell having guideways, a pair of arms adapted to be frictionally held in said guideways, a plate supported by said arms, and 60 oppositely arranged lugs on said plate for guiding and supporting a drill steel, said arms being adapted to be forced completely from said guideways by the forward end of the rock drill. 65

8. In a rock drill, the combination of a shell having guideways, a pair of pivotally connected arms adapted to extend beyond the end of said shell and lie in a plane substantially parallel to the plane of the shell 70 guideways, manual means for causing said arms to be frictionally held in said guideways, a plate supported by said arms and connected to one of said arms to move therewith, and oppositely arranged lugs carried 75 by said plate for supporting and guiding a drill steel.

CLARENCE V. PLUMB.
